TALKING MACHINE WITH REPETITION DEVICE

Joseph Louis Routin, Paris, France

Application November 3, 1936, Serial No. 108,987
In France November 23, 1935

6 Claims. (Cl. 274—15)

The present invention relates to a sound reproducing machine provided with a mechanism rendering it possible to repeat automatically either a predetermined passage of a record or the whole of said record, wherein the arm carrying the sound box of the machine is operated by a cam device constituting an adjustable abutment, in such manner as to raise it from the record at the termination of an audition, move it to a different radial position on the record and to replace it on the record.

The principal feature of the improvement according to the present invention resides in the fact that in a sound reproducing machine of the aforesaid kind, the adjustment of the position of the cam device constituting an adjustable abutment instead of being effected by means of a worm as in known devices is effected by means of a lever co-operating with said cam device and adapted to be set in any desirable suitable position.

A further feature of the invention resides in the fact that the repetition mechanism is actuated by a mechanical clutch controlled by a chronometric device adapted to render it possible to obtain at will adjustable durations of auditions, varying for example from one to twenty seconds.

A still further feature of the invention consists in providing in a sound reproducing machine a device comprising a cam device which co-operates with a hammer mounted on a resilient member, the said hammer serving to cause the opening of the box which contains the reserve needles.

The schematic Figure 1, given by way of example, shows how the mechanism may be constructed, which is used in order to effect successively the raising of the needle, its radial displacement towards the periphery of the record, and then its replacement again in contact with the record, without any shock occurring.

The schematic Figures 2 and 3 given by way of example show respectively, in partial elevation and in partial cross section, taken on line X Y of Fig. 2, how the automatic actuation of the mechanism shown in Fig. 1 could be brought about.

The schematic figure 4, given by way of example, shows an alternative arrangement of the motor control, shown in Fig. 2.

The schematic Figures 5 and 6 given by way of example show complementary parts of the mechanism shown in Fig. 2.

The schematic Figures 7, 8, 9 given by way of example, show how the improvement relating to

the shaping of the abutment and the selector with graduated dials could be carried into effect.

The schematic Figure 10 shows an embodiment of an alarm arrangement indicating the moment when the needle should be changed.

The schematic Figure 11 shows how the different parts could be arranged.

The schematic Figure 12 shows how the lighting of the dials could be made.

In Figure 1, *a* denotes a gramophone pick-up mounted on an arm *b* which is adapted to move about an axis *c* supported by a vertical rod *10*; *12* denotes a vertical rod carried by *10*; *d* denotes a horizontal support integral with a sleeve *3* which is adapted to rotate in a fixed vertical bearing *4*; *e* denotes a horizontal knife edge member carried by *d*; *f* denotes a longitudinal slot formed in *d* through which the rod *12* passes; *13* denotes a cylindrical member which is adapted to rotate around *4* and is provided with two guide edges *15* and *115* inclined in opposite directions and arranged in such a way as to constitute a V-shaped notch; *117* denotes a lever rendering it possible (as will be explained later on) to fix *13* in any selected rotary position; *20* denotes a lever which is adapted to rotate around a fixed horizontal axis *21* and which carries a roller *22*; *10* denotes a boss carried by *20* and against which *10* is constantly applied by a spring *10'*; *50* denotes a cam which can rotate around *46* and *30* which is provided along its longest radius with a notch *52* into which the roller *22* can enter.

The mode of operation may be explained as follows:

By rotating *50*, vertical displacements of *10* are produced. A downward vertical displacement of *10* starting from the highest position produces first a pivoting of *b* around the point of the needle bearing on the record, then a vertical raising of the needle by a rocking of *b* around the knife edge *e*, and finally, a helicoidal displacement of the needle, the horizontal component of which is produced by the action of one of the guide slopes *15* or *115* upon the rod *12*. The distance apart of the upper edges of the guide slopes *15* is sufficiently great to ensure that the rod *12* is always located above one of them.

When the rod *10* rises, the needle goes down and lands on the record without any shock and this, at a distance from the centre which is determined by the position given to *13*.

In Figures 2 and 3, *46* denotes an axle carried by a suspension loop *47* fixed underneath the upper plate *5* of the gramophone and this axle is driven in the direction of arrow *f* by the gramo-

phone motor, in such a way as to rotate one turn when the record makes N turns; 48 denotes a ratchet wheel comprising N teeth fixed upon 46; 49 denotes a pinion fixed on 46; 50 denotes a cam integral with sleeve 51 freely mounted upon 46; 52 denotes a notch which is provided in the periphery of 50 and into which roller 22 is adapted to enter (see Fig. 1); 53 denotes a double-armed pawl which carries a front pin 54 and a rear pin 55 and which is adapted to rotate around an axis 56 mounted in a sleeve fixed on 50, whilst remaining constantly urged by a spring 56' in the direction of arrow f_2 ; 57 denotes an abutment which is integral with an arm 58 and which is adapted to rotate around an axis 59, whilst remaining constantly urged in the direction of arrow f_3 by a spring 58' which tends to apply it against a stop pin 60; 61 denotes a suspension loop which is adapted to oscillate around an axis 62; 63 denotes an axle which is mounted upon 61 and which carries a gear 64 which is adapted to come into mesh with 49; 65 denotes a coil spring which, through its connection at one end to the suspension loop 61 and at its other end to the hub 25 of the gear 64, tends constantly to cause 64 to rotate in the direction of arrow f_4 ; 66 denotes a spring which is fixed on the one hand to the fixed suspension loop 47 and on the other hand to the oscillating suspension loop 61 and which tends 30 to bring 64 into mesh with 49; 67 denotes a lever which is adapted to rotate around an axis 68 fixed upon 61 whilst remaining constantly urged by a spring 67' in the direction of arrow f_5 ; 69 designates a projecting member which is integral with 35 67 and which is adapted to be raised by a pin 70 carried by 50; 71 denotes a piece fixed upon 47 and arranged in such a way that when the extremity of 67 abuts against it, 64 cannot come into contact with 49; 72 denotes a slot provided in 69 40 in order to render it possible for 70 to escape after having displaced 67 to the right; 73 denotes a pin fixed to 64 and arranged in such a way as to abut against 58 when 64, which is driven by 49 rotates in the opposite direction to that of arrow f_4 and the tension of spring 65; 74 denotes a pin which is fixed to 64 and which, when 64 is brought back by spring 65, bears against an arm 75 mounted on an axle 76; 77 denotes a worm gear wheel which is mounted upon 76 and which 50 can be rotated by driving a screw shaft 78; 79 denotes a graduated drum which renders it possible to find opposite a fixed index the position given to 75; 80 denotes a lever mounted upon the pick-up arm which rotates in the direction of arrow f_6 55 when the needle comes near to the centre of the record; 81 denotes a spiral cam which is adapted to be set by a knob 82 mounted upon a graduated dial 83 and which presses on the rear arm 84 of abutment 57, when the needle reaches the end of the record; 85 denotes a lever integral with 61; 86 denotes an insulating member which is secured to 85 and which produces the closing of a switch 87 when 85 is lowered; 88 denotes a lever having a stopping notch 89, which is adapted to rotate around 90 and which is constantly driven in the direction of arrow f_7 by a spring 88'; 91 denotes a lever integral with 88 which is adapted to be raised by a cam 92 which can be rotated by operating an actuating knob 93; M denotes the electric motor which actuates the gramophone; 94 denotes two feeding terminals; 95 denotes a switch actuated by hand, which can be maintained open or closed according to the position given to lever 75; 96; 97 denotes a flexible cord carrying two leads.

The mode of operation may be explained as follows:

In the position represented on Figs. 2 and 3, the cam 50 is prevented from rotating and (see Fig. 1) as 22 is raised, the needle is in contact with the record. Furthermore the gear 64 being in mesh with 49, if the motor is in action, the pin 73 moves in the direction opposite to f_4 . As soon as this pin 73 reaches the arm 58, the abutment 57 is driven in the direction opposite to f_3 ; the pawl 53, the pin 55 of which is freed, rotates in the direction of f_2 and its front pin 54 comes into contact with the ratchet wheel 48, thereby interlocking 50 with 48. Cam 50 being driven in the direction of f_1 , the pin 70 by pushing on the extremity of 61, displaces 61 towards the right and removes 64 from 49. As soon as gear 64 is disengaged, pin 74 briskly comes back in the direction of f_4 under the action of spring 65 until it is stopped by arm 75. The action of 70 upon 67 continues however, after the disengagement of 64 until the extremity of 67, by rotating in the direction of f_5 slips off 71. Then the pin 70 disengages from 67 by passing through notch 72, and after having made almost a complete turn, raises 67 by engaging the projecting member 69. The spring 66 brings 61 briskly back towards the left, thus enabling 49 to re-engage 64. Immediately after this, 55 abuts against 57, the pin 54 of pawl 53 is uplifted and 50 is temporarily brought back to rest in its initial position, when 22 comes to lodge in the notch 52. The pin 73 being again displaced in the opposite direction to f_4 , the same series of phenomena will be reproduced indefinitely, and to sum up, it will be clear that the arrangement produces alternatively, on the one hand, the holding at rest of the cam 50 in a position which puts the needle in contact with the record during an interval of time which is indicated on 79 and which can be adjusted at will, by driving 71, in order to displace 75, and, on the other hand, the rotation of cam 50 in direction of f_1 , in a pre-determined time which corresponds to that which has been allowed in order to effect the operations consequent upon the displacement of the gramophone arm.

In order to repeat uninterruptedly the audition of the whole record, it is only necessary to operate 93 in such a way that 89 maintains 85 uplifted, thereby preventing 64 from returning into contact with 49. The repetition is obtained in this case by the action, at the end of the record, of the cam 81 upon arm 84 of abutment 57; and it is clear that by rotating 81, it is possible to adjust this action with precision according to the distance existing between the centre of the record and the last furrow of the record.

It should be remarked that the ratchet wheel 48 having N teeth and making one turn when the record makes N turns, it will be seen that it will always be along the same radius that the contact will be re-established between the needle and the record.

The mode of operation of the motor may be explained as follows:

According to the connections indicated on Fig. 2, it is seen that the repetitions will continue until the two switches 87 and 95 are simultaneously open. It follows, that in case of opening of 70 switch 95, the stopping will not be effected immediately, but only after the opening of switch 87, that is to say, at the end of the audition of the paragraph being studied.

The arrangement thus constitutes a reliable 75

control of the motor which ensures accuracy in the interruption, as well as in the resuming of the auditions.

In Figure 4, 265 denotes an operating lever which is adapted to rotate around 266 and which is provided with a stop 267; 268 denotes a bent spring which, by co-operating with two lugs 269 and 270 fixed to 265, renders it possible to stop 265 in accordance with three different positions; 271 denotes a switch which is arranged in the circuit of the motor of the gramophone and which is mounted upon lever 265; 272 denotes a bent lever which is adapted to rotate around 273 and which carries a roller 274 which is maintained, by a spring 272 constantly applied against cam 50; 275 denotes an insulating piece which is fixed to 272 and which causes the opening of 271 when, lever 265 having been pushed towards the left, roller 274 is brought to the end of its downward course by the rotation of 50; 276 denotes a manual controlling lever which is integral with 51. The application of this alternative structure comprises the omission of switches 81 and 95 represented on Fig. 2.

25 The mode of operation of this alternative structure is as follows:

When 265 is pushed towards the right, the motor and the repetition mechanism work without interruption, because 271 remains closed and 30 the length of arm 267 is adjusted in such a way that in this position it cannot stop 55.

When 265 is in the median position, 267 by stopping 55, causes the stopping of the repetition mechanism at the end of the paragraph on study 35 and after the lifting of the gramophone arm; but the motor continues to rotate, because, in this position 275 does not reach 271.

When 265 is pushed towards the left, the repetition mechanism is stopped as explained above; 40 and, moreover, the motor is itself stopped by the action of 275 upon 271 when 274 is brought to the end of its course by the rotation of 50, that is to say, at the moment when the pick-up arm has just completed its lifting movement.

45 The advantage presented by the adjunction of lever 276 consists, particularly, in rendering it possible, in the course of a recapitulation, to take up again instantaneously any passage of the record.

50 In Figure 5, where a certain number of parts represented in Fig. 2, are found again, 105 denotes a second ratchet wheel which is fixed to 48 and which carries a larger number of teeth; 106 denotes a fixed inclined guide (mounted upon 47) against which the end of the axle 56 of the pawl 53 is, at each turn of 50, temporarily applied by a spring 55; 54 denotes, as previously, one of the pins or beaks of the pawl, but its shape is such that it engages first, with 105, and then with 48, 55 when 50 has traversed in the upward direction the guide slope 106.

It is obvious that the adjunction of this arrangement renders it possible to adjust the duration of the audition with a greater precision, as the cam 50 is driven on as soon as 54 falls into one of the teeth of 105.

In Fig. 6, 107 denotes a metallic sector integral with 3; 108 denotes a lever which is adapted to rotate around a horizontal axle 109 and which 70 carries at its end a resilient braking member 110; 111 denotes a spring which tends to pull 110 away from 107 and to apply 108 against an abutment with 112; 113 denotes a cam which is integral with the cam 50 shown in Fig. 1 and which is associated with it so as to occupy the position in

which it is shown when the needle is in contact with the record.

The cam 113 being carried with cam 50 in the direction of arrow f_1 it is immediately seen that, as soon as cam 113 has rotated half a turn and 5 until it has come back into the position in which it is shown, that is to say, during all the time that the descending movement of the needle lasts, all movement of rotation of the pick-up arm will be rendered impossible, due to a brake-couple 10 developed by the contact between 110 against 107. It is further clear that complete freedom will be given to the pick-up arm as soon as the needle has made contact again with the record.

In Figs. 7 and 9, 118 denotes a graduated toothed 15 sector which is supported by two small columns 119 and 120 on the upper plate 5 of the gramophone; 121 and 122 denote two arcuate slots made in 118; 123 denotes a pawl pivotally mounted on an eccentric 151 carried by an axle 150; 124 denotes a spring arranged in such a way as to apply 123 against the teeth of 118; 125 denotes a small lever which renders it possible to take 123 away from 118; 126 denotes an abutting pin fixed to 118; 127 denotes a spiral cam which can be rotated by operating 128; 129 denotes a spring which maintains 126 applied against 127; 130 denotes a graduated dial integral with 128; 131 denotes a circular indicating line which is traced on 118 and which is used as an index for 30 the readings made upon 130; 149 denotes a milled knob which can rotate around an axle 150 which is mounted upon 117 and which carries an eccentric wheel 151 on which the pawl 123 pivots; 152 denotes an indicating arrow traced on 149 in 35 order to render it possible to gauge the magnitude of the displacement communicated to 117 by operating 149.

The cam 127 being shaped in order to permit of displacing 118 through an angle equal to that corresponding to the width of a tooth, it will be obvious that the beginning of the audition can be adjusted at will, and it will be noted that this tandem association of two adjusting systems 123, 127 rendering possible a fine relative adjustment, 45 presents the advantage of uniting very great precision with very great rapidity of operation.

It will further be seen that by operating 149, it is possible to communicate small movements to 117, which will render it possible, by taking the 50 audition itself as a guide, to correct, in case of need, all the small deviations which might arise (for example in case of displacement of the axis of the turntable carrying the record) and to ensure the correct resumption of the audition, 55 whilst having always for each paragraph the same marks, both on 118 and on 130.

As an alternative, 149 might be replaced by a simple screw mounted upon 126 the end of which might be supported by cam 127.

From Fig. 8 it will be seen that, in its descending movement, the member 12 places itself exactly along the bisector of the angle formed by 15 and 115. It is, moreover, seen that in order to prevent all danger of scratching the record it is only 65 necessary to make the distance d sufficiently great to ensure that the needle is completely removed from the record before 12 can engage with 13. It must be noted that by giving a sufficient width to the opening of the notch constituted by the 70 two guiding slopes 15 and 115, it will be possible to pass from the first paragraph to the last, or the contrary, without it being necessary to act upon the gramophone arm.

It should also be noted that the marks of the 75

graduation carried by 118 are continued inwards to facilitate the reading in front of the index constituted by the extremity of the arm 80 of the marking of the passage in course of audition. 5 This marking will be in particular very useful in order to obtain, during a recapitulation, the immediate taking up again of a predetermined passage.

10 In order to be able to use to the best advantage the mechanism serving to adjust with precision the beginning of each audition, it is convenient to mark upon dial 130, ten equi-distant indicating lines and to shape cam 127, in such manner that the displacement communicated to sector 118, by 15 passing upon 130, from division 1 to division 10, is the same as the displacement obtained by displacing pawl 123 by one tooth upon sector 118.

It is then only necessary to mark on the written text corresponding to the studied record, the words with which the audition begins when, the graduation of 130 being maintained at zero, 123 is placed successively in the different notches of sector 118.

20 It is, in fact, always easy to estimate, in tenths of the interval comprised between two successive markings, the position of the word with which the paragraph which it is desired to study begins. In order to facilitate this estimation, it is possible, to transcribe the text in question by arranging it 25 in such a way that each line corresponds, for example, to two-tenths of the interval comprised between two successive markings.

30 In Figure 10, 39 denotes a lever which is pivoted around 40, which bears a locking hook 41 and which is constantly under the influence of a spring 42; 43 denotes a receptacle containing needles in stock, 44 denotes a cap which is adapted to rotate around 45 and which is held down by 41 against the action of a spring which constantly 35 tends to lift it; 132 denotes a cam driven by the gramophone motor, which turns around 39' and turns through a complete revolution during the time corresponding to the wearing out of a needle (for example, 5 to 10 minutes); 133 denotes a 40 lever which is adapted to pivot around 134 and which is maintained applied against 132 by a spring 135; 136 denotes a spring member which is fixed to 133 and which carries at its extremity a heavy bob 137.

45 45 It will be seen that the rotation of 132 will cause at regular intervals (each time that it is convenient to change the needle) a sudden impulse to be applied to the bob 137 which will have the result of 44 being raised by its spring. It will, 50 moreover, be seen that immediately after it has been raised, 44 can again be maintained by 41 in its closing position.

55 From Figure 11, wherein 130 denotes the operating knob which acts upon 118, and 139 denotes a volume control knob, it will be seen how the different pieces before mentioned may be arranged in order to facilitate the adjusting operations. In this figure the reference numerals 41, 44 and 45 denote the same parts as those indicated in the other figures by these reference numerals, and the reference numeral 138 denotes the control knob of the screw shaft 78.

60 In Figure 12, 140 denotes a box containing the gramophone mechanism; 141 denotes the cover of 140; 142 denotes an electric lamp provided with a light-shade mounted at the extremity of a foldable support 143, the folding operation of which controls a switch 144, the current being led up to the lamp on the one hand, by a hinge member 75 145 and on the other hand, by a supporting mem-

ber 146, which maintains the cover lifted; 147 and 148 denote two spools which are used for winding up the conductors before closing down the gramophone box.

It will be noted that the lamp is so arranged as to illuminate the whole set of graduations.

What is claimed is:

1. In a sound reproducing machine, a rotatable support for a sound record thereon and means for rotating it, a sound reproducer and an arm supporting it for lateral movement across a record on the support, said reproducer being also mounted for movement toward and away from operative engagement with said record, and means for automatically moving said reproducer and the 10 arm supporting it through a repetitive cycle to repeat any selected passage of the record, said means including an adjustable cam cooperating with said arm to determine the starting position of the arm and reproducer at which the reproducer is moved into operative engagement with the record at the beginning of the selected passage, said arm having a part engaging said cam to swing the arm and reproducer laterally to, and hold it in, the starting position in the movement of the reproducer away from operative engagement with the record. 15

2. In a sound reproducing machine, a rotatable support for a sound record thereon and means for rotating it, a sound reproducer and an arm supporting it for lateral movement across a record on the support, said reproducer being also mounted for movement toward and away from operative engagement with said record, and means for automatically moving said reproducer and the 20 arm supporting it through a repetitive cycle to repeat any selected passage of the record, said means including an adjustable cam cooperating with said arm to determine the starting position of the arm and reproducer at which the reproducer is moved into operative engagement with the record at the beginning of the selected passage, said arm having a part engaging said cam to swing the arm and reproducer laterally to, and hold it in, the starting position in the movement of the reproducer away from operative engagement with the record, and a brake device 25 operative in synchronism with the movements of the arm and reproducer and arranged to restrain the arm against lateral movement except when the reproducer is in operative engagement with the record. 30

3. In a sound reproducing machine according to claim 2 in which the movement of the reproducer toward and from the record is controlled by an intermittently driven rotating cam and the brake device is operated by a cam driven in synchronism therewith. 35

4. In a sound reproducing machine, a rotatable support for a sound record thereon and means for rotating it, a sound reproducer supported for lateral movement across a record on the support and for movement toward and away from operative engagement with said record and means for automatically moving said reproducer through a repetitive cycle to repeat any selected passage of the record, said means including an adjustable abutment cooperating with the reproducer when it is out of operative engagement with the record to determine the position at 40 which the reproducer is moved into operative engagement with the record at the beginning of the selected passage, said abutment being adjustable at any time in the repetitive cycle and without action on the reproducer while the same 45 45

is in operative engagement with the record, said means further including a driven shaft, an electric motor for driving said shaft, a cam on said shaft for effecting the approach and separation movements of said reproducer and record, and a clutch for connecting said cam to the shaft, a switch for controlling said motor and manually operable means controlling said switch and clutch, and movable to three different positions, said manually operable means when moved to one position opening the switch and stopping the motor, in another position leaving the switch closed and the motor running but releasing the clutch, and in a third position out of operative relation to the clutch and switch, in which position the repeat means can operate continuously.

5. In a sound reproducing machine, a rotatable support for a sound record thereon and means for rotating it, a sound reproducer and an arm supporting it for lateral movement across a record on the support, said reproducer being also mounted for movement away from and toward operative engagement with said record, and means for automatically moving said reproducer 20 supporting it through a repetitive cycle to repeat any selected passage of the record, said means including a motor driven shaft, a rotary cam mounted thereon, a clutch for intermittently connecting said cam to the shaft, a connection between said cam and arm for causing the separation and approach movements of the reproducer and record during the rotation of the cam, and a chronometric device automatically controlling the time for throwing in said clutch 25 independently of the movement of the arm, and a manually operable means for rendering the chronometric device inoperative, a manually operable lever for throwing in the clutch, said lever pro-

jecting into the path of an arm swinging with the reproducer, said arm carrying a stop so related to the reproducer as to engage the lever to stop the lateral swing of the reproducer at the end of the record.

6. In a sound reproducing machine, a rotatable support for a sound record thereon and means for rotating it, a sound reproducer and an arm supporting it for lateral movement across a record on the support, said reproducer being also mounted for movement away from and toward operative engagement with said record, and means for automatically moving said reproducer and the arm supporting it through a repetitive cycle to repeat any selected passage of the record, said means including a motor driven shaft, a rotary cam mounted thereon, a clutch for intermittently connecting said cam to the shaft, a connection between said cam and arm for causing the separation and approach movements of the reproducer and record during the rotation of the cam, and a chronometric device automatically controlling the time for throwing in said clutch independently of the movement of the arm, and a manually operable means for throwing out the chronometric device, a manually operable lever for throwing in the clutch, said lever projecting into the path of an arm swinging with the reproducer, said arm carrying a stop so related to the reproducer as to engage the lever to stop the lateral swing of the reproducer at the end of a record, and fine adjustment means for accurately adjusting said stop with relation to said swinging arm, said adjustment means including a dial and pointer to readily make visible the position of the stop.

JOSEPH LOUIS ROUTIN.
